UNITED STATES PATENT OFFICE.

EDWARD F. DUDLEY, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

INK-DISTRIBUTING-DRUM-VIBRATING MEANS.

Application filed March 3, 1921. Serial No. 449,512.

To all whom it may concern:

Be it known that I, EDWARD F. DUDLEY, a citizen of the United States, residing at Oak Park, in the county of Cook and State 5 of Illinois, have invented certain new and useful Improvements in Ink-Distributing-Drum-Vibrating Means, of which the following is a specification.

In printing-press inking mechanisms, it is 10 customary to use one or more reciprocating, rotating drums in contact with companion inking rollers, the back and forth sliding or 15 vibrating movements of the drum being employed to assure the even spread and distribution of the ink by working it alternately in opposite directions on the surfaces of the contacting rollers.

It is of advantage and useful to provide 20 simple means for permitting adjustment of the mechanism which effects the reciprocatory movements of such a vibratory drum, whereby the amount or degree of ink spreading or distribution may be readily controlled, in fact, in some cases, it may be necessary or convenient to eliminate such vibratory travel entirely.

One purpose of this invention is, therefore, to supply a simple, efficient, readily-adjustable means for producing such sliding 30 movements of the drum or roller specified.

In its preferred incorporation in physical form, the invention comprises the employment of two cam mechanisms in series or tandem arrangement adjustable relatively 35 to one another to vary or eliminate the stroke or lengthwise travel of the vibratory drum or roller.

In the associated drawing, throughout the plurality of figures of which the same reference characters refer to like parts, such drawing forming a part of the present specification, a desirable embodiment of the invention has been presented.

In the drawing:

45 Figure 1 is a partial elevation and partial section showing the several cooperating elements entering into the improved construction;

50 Figure 2 is an enlarged section through the cam-shaft and its cam structure illustrating the means provided for the angular adjustment of the cam; and

Figure 3 is a section on line 3—3 of Figure 2.

As is fully illustrated in such drawing, 55 the construction includes a frame with spaced or separated portions 11 and 12 having aligned bearings for a rotary shaft 12' revolved from an upright drive-shaft 13 through coacting or intermeshing bevel- 60 gears 14 and 15.

To this shaft 12' an ink-distributing drum or roller 16 is splined so as to be revolved by the shaft, at the same time being capable of longitudinal or lengthwise movement 65 thereon to assist in its ink spreading and distributing function.

Fixed to the drum or roller is a cam 17 having a cam-groove 18, and on shaft 12' is a similar, angularly-adjustable cam 19 with 70 a cam-groove 21 and having in a side face a number of cylindrical holes or recesses 22, 22 arranged in the arc of a circle concentric with the axis of the cam, any one of which cavities is adapted and intended to receive 75 a retaining pin or lug 23 projecting side- wise from a collar 24 splined to and hence, when freed, lengthwise movable on the shaft and normally held against a shoulder of the latter by a washer 25 and a companion nut 20 26 screwed on the reduced, threaded, terminal part 27 of the shaft.

By removing or unscrewing the nut sufficiently, the collar may be shifted lengthwise 85 of the shaft enough to temporarily withdraw the retaining or holding pin 23 from the recess of the cam, thus enabling the latter to be adjusted or turned on the shaft to a new angular position, whereupon the collar is replaced, the pin entering a new recess, 90 and the parts are tightened in position by screwing up the nut.

The device includes also a bearing 28 in the stationary frame-work accommodating a sliding, rotary shaft 29 equipped at one 95 end with a roller 30 fixed thereto and engaging the groove 18 of the drum cam 17.

In similar manner the opposite end of the shaft has a roller 31 projecting into the groove 21 of the shaft cam 19.

Shaft 29 not only reciprocates in its stationary bearing but it also rotates therein by reason of the frictional engagement of its rollers with the walls of the cam grooves in which they fit.

Under usual or normal conditions the two cams thus arranged in series or tandem relation are so associated with one another

that, as the shaft and its drum revolve in unison, the latter is caused to reciprocate lengthwise on the shaft by reason of the action of cam 19 causing the longitudinal 5 shifting or displacement of the shaft or rod 29, which movement through the roller 30 is transmitted by cam 17 to the drum.

The extent or degree of such reciprocation or to and fro movement of the drum may 10 be varied or controlled by changing or modifying the angular position of the shaft cam on the shaft, and, inasmuch as the two cams thus arranged and operable in series are alike so far as the pitch of their cam grooves 15 is concerned, they can be adjusted to wholly neutralize or counteract their action on the drum, and under such circumstances, which are occasionally desirable, the drum does not vibrate or slide back and forth during 20 its rotation.

I desire to make it plain that I have clearly intended by the specification and drawing accompanying this application to 25 illustrate the invention in the best and most practicable form of which I am now aware, but it is to be understood that the invention includes many variations and modifications 30 of this preferred structure, all of which are included within the scope of appended claims.

I claim:

1. In a mechanism of the character described, the combination of a vibrator-drum, means to revolve said drum, means to reciprocate said drum longitudinally comprising two cooperating cam devices arranged in series, connecting means coacting with the cam surfaces of both cam devices, and means 35 to adjust said cam devices angularly rela-

tively to one another to vary the length of 40 the stroke of the drum, substantially as described.

2. In a mechanism of the character described, the combination of a shaft, means 45 to rotate said shaft, a vibrator-drum splined to and slidably on said shaft, a cam rotatable with said shaft, a cam rotatable with said drum, and cooperating connecting means between said cams, substantially as described.

3. In a mechanism of the character described, the combination of a shaft, means to rotate said shaft, a vibrator-drum splined to and slidably on said shaft, a cam rotatable with said shaft, a cam rotatable with said drum, operating connecting means between 50 said cams, and means to adjust said cams angularly relatively to one another to vary the stroke of said drum, substantially as described.

4. In a mechanism of the character described, the combination of a frame, a shaft, means to rotate said shaft, a vibrator-drum splined to and slidably on said shaft, a cam rotatable with said shaft, a cam rotatable with said drum, a rod slidably mounted in 60 said frame, and means on said rod coacting with both cams, substantially as described.

5. In a mechanism of the character described, the combination of a frame, a shaft, means to rotate said shaft, a cam rotatable 70 with said shaft, a cam rotatable with said drum, a rod slidably mounted in said frame, means on said rod coacting with both cams, and means to adjust said cams angularly 75 relatively to one another to vary the stroke of said drum, substantially as described.

EDWARD F. DUDLEY.
